(57) **CLAIM**

The ornamental design for a display screen or portion thereof with a graphical user interface, as shown and described.

DESCRIPTION

The patent file contains at least one drawing executed in color. Copies of this patent with color drawing(s) will be provided by the Office upon request and payment of the necessary fee.

FIG. 1 is a front view of a display screen or portion thereof with a graphical user interface according to a first embodiment;

FIG. 2 is a front view of a display screen or portion thereof with a graphical user interface according to a second embodiment;

FIG. 3 is a front view of a display screen or portion thereof with a graphical user interface according to a third embodiment;

FIG. 4 is a front view of a display screen or portion thereof with a graphical user interface according to a fourth embodiment;

FIG. 5 is a front view of a display screen or portion thereof with a graphical user interface according to a fifth embodiment;

FIG. 6 is a front view of a display screen or portion thereof with a graphical user interface according to a sixth embodiment;

FIG. 7 is a front view of a display screen or portion thereof with a graphical user interface according to a seventh embodiment;

FIG. 8 is a front view of a display screen or portion thereof with a graphical user interface according to an eighth embodiment;

(Continued)

FIG. 9 is a front view of a display screen or portion thereof with a graphical user interface according to a ninth embodiment; and,

FIG. 10 is a front view of a display screen or portion thereof with a graphical user interface according to a tenth embodiment.

The bold dashed broken line box forms no part of the claimed design. The bold dashed broken lines within the box form no part of the claimed design. The remaining broken lines illustrate portions of the display screen or portion thereof with a graphical user interface that form no part of the claimed design.
